UNITED STATES PATENT OFFICE.

FRANK A. BORST, OF SOUTH BEND, INDIANA, ASSIGNOR TO IDEAL CONCRETE MACHINERY COMPANY, OF SOUTH BEND, INDIANA, A CORPORATION OF INDIANA.

DIVIDING-PLATE FOR BLOCK-MOLDS.

No. 850,206.

Specification of Letters Patent.

Patented April 16, 1907.

Application filed August 20, 1906. Serial No. 331,248.

To all whom it may concern:

Be it known that I, FRANK A. BORST, a citizen of the United States, and a resident of South Bend, in the county of St. Joseph and State of Indiana, have invented a new and Improved Dividing-Plate for Block-Molds, of which the following is a specification.

My invention relates to molds for the forming of building-blocks of plastic material; and the objects of my improvements are to provide means whereby a plurality of blocks can be molded in the same machine simultaneously and to provide means whereby the edges of the molded blocks are prevented from breaking when the dividing-plates are withdrawn.

My invention consists in a mold arranged for the rigid retention of thin dividing-plates and a removable guide through which these plates are withdrawn.

In the drawings, Figure 1 is a plan view of a block-molding machine with the guide placed over a dividing-plate. Fig. 2 is a cross-section on the line 2 2 of Fig. 1. Fig. 3 is a front view of the opened machine. Fig. 4 is a perspective view of a portion of the mold on a somewhat larger scale, showing a dividing-plate and the guide in position. Fig. 5 is a perspective view of the face-plate.

Similar reference characters refer to like parts throughout the several views.

In the drawings, 1 are the legs and 2 the top of the frame of a concrete-block machine. To the rear of the frame is secured the back plate 3, provided with a flange 4. The front plate 5, having a flange 6, is hinged to the frame at 7 and when swung forward to discharging position rests on the arm 8, extending forward from the frame. This front plate has arms or horns 9 formed on it, which arms are adapted when the mold is open to support the end doors or plates 10, which are hinged to the front plate 5 at 11. A face-plate 12, normally resting on the frame, is mounted on the pins 13, secured to the front plate, and a pallet 14 rests against the front plate and on the face-plate. The mold is locked together by means of the cams 15, pivoted on the lugs 16 on the end plates, which cams engage back of the back plate, as shown in Fig. 1.

When the block has been molded, the cam-handles 17 are raised and the front plate swung down to horizontal position, as shown in Fig. 3, together with the pallet 14. The bottom plate is carried up to vertical position by means of the pins 13, and the end plates 10 are permitted to swing down to the position shown in Fig. 3, where they rest on the arms 9. The pallet, and with it the molded block, is now carried away and a new pallet substituted and the mold again closed.

It is often desirable to mold blocks of less length than the interior of the mold, for which purpose the means described below are employed.

The face-plate 12 is provided with slots 18 to receive the lower edge of the dividing-plates 19, while the flanges 4 and 6 of the front and back plates, respectively, are provided with slots 20 to receive the ears 21 of said plates. By these slots the plates may be rigidly held while the plastic material is being rammed in the mold, and the position and number of the slots determine the number of different sizes of blocks that can be molded on one machine.

When the compartments of the mold are filled, the guide-bar 22 is placed over each plate in turn, the hooks 23 on the bar engaging under the flange 4 of the back plate and the dividing-plate 19 passing up through the longitudinal slot 24.

The plastic material has a slight tendency to stick to the dividing-plate, and as a result the upper edges of the blocks tend to break or crumble when the dividing-plate is withdrawn; but by placing the guide-bar 22 over the plate with the hooks 23 under the flange 4 and by pressing down on the handle 25 while the plate 19 is withdrawn the bar resting directly on the blocks adjacent to the plate will prevent all crumbling and breaking. The blocks will be discharged from the mold with sound sharp edges in the manner above described and carried away on the pallet 14.

Having now explained my improvements, what I claim as my invention, and desire to secure by Letters Patent, is—

1. In a building-block mold, the combination of a frame, a back plate having notches at its upper edge, a front plate hinged to said frame and normally parallel to the back

plate, said front plate also provided with notches at its upper edge, end plates, a bottom plate extending across said mold and connected to said front plate and provided with 5 grooves, and a dividing-plate adapted to fit in said groove and provided with extensions to engage the notches in the front and back plates.

2. In a building-block mold, the combination of a bottom and sides, one of the sides 10 having a lateral bead or flange along its upper edge, a dividing-plate adapted to be securely held in said mold to permit the form-

ing of a plurality of blocks simultaneously, and a guide comprising a bar having a slot 15 through which said plate may pass and provided with a hook to engage the bead or flange of the side of the mold.

In testimony whereof I have signed this specification in the presence of two subscribing witnesses.

FRANK A. BORST.
